UNITED STATES PATENT OFFICE.

WILLIAM THORNBURGH, OF ELYRIA, OHIO.

SEMAPHORE-SIGNAL.

SPECIFICATION forming part of Letters Patent No. 308,013, dated November 11, 1884.

Application filed June 6, 1884. (No model.)

To all whom it may concern:

Be it known that I, WILLIAM THORNBURGH, of Elyria, in the county of Lorain and State of Ohio, have invented a new and Improved 5 Semaphore-Signal, of which the following is a full, clear, and exact description.

The object of my invention is to provide a new and improved semaphore-signal for governing and regulating the movements of rail-way-trains at grade-crossings, draw-bridges, block-stations, terminals, switches, &c.

The invention consists in the combination, with an upright frame having tubular standards, of rods sliding in the standards, and 15 wings pivoted in the top of the frame and connected with the rods, which rods are operated by suitable hand-levers.

The invention further consists in providing two single wings and two pairs of wings, in 20 the frame of which wings a single wing and a pair of wings swing from each side of the frame.

The invention further consists in the combination, with the said sliding rods and wings, 25 of a lantern-box held in the upright frame, and of glass slides connected with the vertically-movable rods.

The invention also consists in various parts and details and combinations of the same, as 30 will be fully described and set forth herein-after.

Reference is to be had to the accompanying drawings, forming part of this specification, in which similar letters of reference indicate 35 corresponding parts in all the figures.

Figure 1 is a face-view of my improved railroad-signal, parts being shown in section. Fig. 2 is a side view, parts being shown in section on the line $x-x$, Fig. 1. Fig. 3 is a 40 plan view of the signal. Fig. 4 is an enlarged sectional plan view on the line $y-y$, Fig. 1. Fig. 5 is a detail perspective view of the trundling wheel and its guide. Fig. 6 is an enlarged sectional plan view of the lantern and 45 the slides in the same. Fig. 7 is a cross-sectional elevation of the same on the line $x'-x'$, Fig. 6. Fig. 8 is detail side view of the arrangement of the wings.

An upright frame is formed of four corner-tubes, A, united at the top by suitable cross-pieces, on which a hood, A', is formed for pro-

tecting the pivots of the wings pivoted in the top of the upright frame.

Through the corner-tubes A rods C' C² C³ C⁴, pass loosely in such a manner that they 55 can be worked up and down, which rods are adapted to operate the signals in a manner that will be set forth hereinafter.

To the lower ends of the rods C' C⁴ connecting-bars D' D⁴ are pivoted, which connecting-bars have their opposite ends mounted to rock on a transverse shaft, E, and the said bars D' and D⁴ are provided on the ends mounted to turn on the shaft E with downwardly-projecting arms F' and F⁴, which form an angle with the 65 bars D' and D⁴. Handle-levers d' and d⁴ are rigidly secured or formed on the bars and arms D' F' and D⁴ F⁴ at the angle, whereby the said bars D' D⁴ and their arms F' F⁴ can be operated by means of the said levers d' and d⁴. Counter-balancing-weights G' and G⁴ are suspended 70 from the lower ends of the rods C' and C⁴. The free ends of the arms F' F⁴ are connected by connecting-rods c' c⁴ with grooved wheels b' b⁴, which run in the guide-frames g' g⁴, and the said 75 wheels have their pivots connected by bars h' h⁴, with the inner ends of the levers or bars D' D⁴. The lower ends of the rods C² C³ are pivoted to the inner ends of levers or bars D² D³, also mounted to turn on the shaft E, and provided with arms F² F³, which are connected by rods c² c³ with wheels b² b³ running in guide-frames g² g³, and connected by bars h² h³ with the inner ends of the levers D² D³. Weights 80 G² G³ are secured on the lower ends of the rods C² C³. These levers are preferably surrounded by a suitable casing, I². The shaft E is either journaled in the sides of the casing I² or in suitable supports secured on the bottom of the said casing. The connecting-bars D² D³ 85 and their arms F² F³ are provided with suitable handle-levers, d² d³. On the four tubular standards A two horizontal partitions, H H', are secured, and between the same a casing, H², is arranged, whereby a box is formed which is 90 adapted to receive the lamp I. On two opposite sides of the casing H bull's-eyes or lenses J are held. On each rod C', C², C³, and C⁴ a glass slide, K', K², K³, K⁴, is held, respectively, behind the lens J, the said glass slides 95 projecting in opposite directions and having their free ends guided in grooved pieces k,

formed on the inner surface of the casing H². On the top plate or partition, H', a chimney or hood, i, is formed over the lamp I. The lenses J must be so arranged that the light-
5 rays passing through the same are thrown in the direction of the length of the track. In the top of the frame formed of the tubular standards a transverse shaft, L, is secured, on which are loosely mounted six wings, M' m'
10 M² M⁴ M³ m³. The wings M' m' form one signal, the wings M³ m³ another, and the wings M² and M⁴ each form a separate signal; or, in other words, when the signal is given by the arms M' m' and M³ m³, two arms are always re-
15 quired to complete the signal. The wings M² and M⁴ are pivoted at their inner ends on the longitudinal central line to swing freely on the shaft L, and are provided with an upward-projecting lug, N² or N⁴, connected by a
20 rod, O² or O⁴, with the corresponding vertical rod, C² C'. The wings M' m' M³ m³ are also pivoted to swing loosely on the shaft L, and the wings M' M³ are provided with upwardly-projecting lugs N' N³, respectively, which are
25 connected by connecting-rods O' O³ with the upper ends of the rods C' C³. The wings m' and m³ are each provided with a short segmental slot, P' or P³, into which slots pins Q' or Q³ pass from the wings M' M³. The wings
30 M' m' and M³ m³ are painted red, and the wings M² M⁴ are painted green. The signal-wings M', m', and M² swing from one side of the standard, and the signal-wings M³ m³ M⁴ swing from the other side of the standard.
35 The operation is as follows: If a signal is to be given by means of two arms—for instance, M' m'—the corresponding lever, d', is swung in the direction of the arrow a', whereby the roller b' will be moved in the direction of the arrow
40 a², whereby the lower end of the bar h' is moved in the direction of the arrow a², thus permitting the weight G' to move downward, thereby pulling the corresponding rod, C', downward. By this movement of the rod C' the connecting-rod O' is pulled downward, and swings the wing M' into the position X in Fig. 8. When the wing M' is in this position, the lower end of the slot P' strikes against the pin Q' on the wing m', and the wing m' will now swing
45 with the wing M', whereby the wing M' is brought into the position shown at Y in Fig. 8, and thereby its wing m' is brought into the position shown at X, Fig. 8; or the signals are in the same position as shown in Fig. 1. At the same time that the rod C' is moved downward the glass plate K' is moved downward and will be held behind the lens J. The glass plate K' is colored red to correspond with the color of the wings M' m', so that a red light
50 will be shown at night during the time that the wings M' m' are in position to give the signal. If the wings M' m' are to be swung down, the lever d' is swung in the inverse direction of the arrow a', whereby the rod C' is raised and the slide K' is also raised. If the signal is to be given by means of the wings M'
55

m³, the slide K' will be lowered in the manner described above. If the signal is to be given by means of the single wing M², the lever d' is swung up in the inverse direction of the arrow a², whereby the inner end of the lever D' is swung down, and at the same time the roller b' is moved in the direction of the arrow a², and thereby the rod C' is moved downward, and the wing M² is swung into the horizontal position. At the same time the rod C' is moved downward, its slide K², which is green, is placed behind the bull's-eye or lens J, so that the signal will show a green light. If the signal is to be removed, the wing M² is 80 swung down by moving the rod C' upward, which is accomplished by swinging the lever d' in the direction of the arrow a².
85 In my apparatus I have signals for trains moving in two directions, the wings M' m' M² being for trains running in one direction, and the wings M³ m³ M⁴ being for trains running in the opposite direction. For example, if a two-wing signal is shown by the wings M' m', the corresponding single wing is lowered; but 90 the other signal-wing, M⁴, may be raised or lowered, or the other double wing, M³ m³, may be raised or lowered. The single wings are thus entirely independent of each other. It is evident that the green and red signals on the 95 same side of the signal-standard will not be used at the same time; but the green and red signals at opposite sides of the signal-standard can be used at the same time, as may be desired.
100

The above-described signal can be erected on the ground adjoining the station or a block-signal line, &c.; or it can be erected on top of a building, or in any other prominent place. It can be made of any desired height, and the 105 wings, lamps, &c., can be made of any suitable size, as may be necessary.

Instead of operating the rods directly from the hand-levers, as shown, suitable connecting-rods may be interposed between the hand-levers and the rods for operating the wings.
110

Having thus described my invention, what I claim as new, and desire to secure by Letters Patent, is—

1. In a semaphore-signal, the combination 115 of a tubular standard, a signal-wing pivoted near the upper end of the standard, a sliding rod arranged in the standard and connected to one end of the wing by a pivoted arm arranged above the wing, to adapt the rod to elevate the wing by being drawn downward, substantially as shown and described.

2. In a semaphore-signal, the combination 125 of a tubular standard, a signal-wing pivoted near the upper end of the standard, a sliding rod arranged in the standard and connected to one end of the wing by a pivoted arm arranged above the wing, a weight attached to the lower end of said rod, and means, substantially as described, for supporting the rod and weight 130 temporarily in a raised position, substantially as specified.

3. A semaphore-signal consisting of a frame having tubular standards, sliding rods arranged in the standards, pivoted wings located at the upper ends of the standards and 5 connected to the rods, colored-glass slides connected to the rods, and lenses or bull's eyes, and a lantern, arranged as shown and described.

4. A semaphore-signal constructed with a 10 frame having tubular standards in which standards rods slide, a separate lever for operating each rod, and wings connected with the rods, substantially as herein shown and described.

15 5. In a semaphore-signal, the combination, with a vertically-sliding rod and a pivoted wing connected to and operated by said rod, of a second wing mounted on the pivot of the first wing and connected to said wing, substantially as described, whereby the wings 20 will be successively operated, as set forth.

6. In a semaphore-signal, the combination, 25 with a tubular standard, a pivoted signal-wing provided with a lateral pin, a sliding rod arranged in the standard and connected to said wing, and means for operating said sliding rod, of a second wing provided with a segmental slot to receive the pins of the first wing, substantially as herein shown and described.

30 7. In a semaphore-signal, the combination, with tubular standards, four sliding rods, and four pivoted wings connected and operated by said rods, of two additional wings connected to two of the first-named wings, to be operated successively thereby, substantially as herein shown and described.

8. In a semaphore-signal, the combination of 35 a frame having tubular standards and a lantern-box held on the said standards, sliding rods in the standards, wings connected with the rods, and slides secured on the rods within the lantern-box, substantially as herein shown and described.

40 45 9. A semaphore-signal constructed with a frame having tubular standards, a lantern-box held on the said standards, sliding rods in

the standards, wings connected with the rods, glass slides secured on the rods within the lantern-box at opposite sides of the box and 50 at opposite ends of the slides, and of guides formed on the sides of the box for the purpose of guiding the free ends of the slides, substantially as herein shown and described.

10. In a semaphore-signal, the combination, 55 with a supporting-frame and four vertically-sliding rods, of a single wing, and a pair of wings arranged on each side of the frame and connected together and to the said sliding rods, substantially as herein shown and described.

11. In a semaphore-signal, the combination, 60 with a pivoted wing, of a vertically-sliding rod connected with the wing, a weight secured on the lower end of the rod, a lever pivoted to the lower end of the rod and connected with a handle-lever, and a brace-bar pivoted to the inner end of the lever at the lower end of the rod, which brace-bar is provided on its lower end with a roller, substantially 65 as herein shown and described.

12. In a semaphore-signal, the combination, 70 with a pivoted wing, of a vertically-sliding rod connected with the wing, the weight G', secured on the lower end of the rod, the lever 75 D', having one end pivoted to the lower end of the rod, the handle-lever d', the arm F', the rod c', pivoted to the free end of the arm F', the roller or wheel b', pivoted to the inner end of the rod c', the guide g', and the brace-bar h', 80 pivoted to the inner end of the lever D', and to the inner end of the rod c', substantially as herein shown and described.

13. In a semaphore-signal, the combination, 85 with a suitable upright frame, of a sliding rod connected with a single wing pivoted in the said frame, and of an additional sliding rod connected with two wings pivoted in the said frame, substantially as herein shown and described.

WILLIAM THORNBURGH.
